CLOTHES WRINGER FOR WASHING MACHINES.

Application filed February 18, 1921. Serial No. 445,984.

This invention relates to power operated wringers for domestic clothes washing machines.

With the introduction of power washing machines, the construction of the wringer used with such machines has ordinarily followed along the conventional lines of the old hand operated wringer, employing similar spring arrangements for maintaining pressure on the rolls, and rolls of much the same size and hardness. Such a wringer is dangerous to use, because it is so much easier to feed the wringer by pushing the material directly between the rolls with the fingers, 15 that the operator sometimes carelessly or accidentally gets the fingers so close as to be gripped by the rapidly moving surfaces of the rolls, with the result that the fingers, hand, and sometimes the arm, are drawn in 20 between the rolls. With the ordinary type of power operated wringer, with which I am familiar, such an accident is almost certain to cause serious injury, because of the heavy pressure between the rolls which rapidly increases as the rolls separate and is particularly injurious since the rolls are relatively 25 hard and unyielding.

With the idea of preventing such accidents, or at least reducing the injury resulting, auxiliary safety pressure release devices have been proposed; but even with such devices, serious accidents often occur. For one thing, such safety device can not ordinarily be operated quickly enough to 30 prevent serious damage. Also, such devices are very rarely used, and consequently are not always maintained in the proper operating condition, so that when needed, they will bind or jam. Further, since the safety 35 device is never used under ordinary conditions, the operator in the emergency often forgets all about the safety pressure release, and tries to stop the wringer in the accustomed way, that is, by operating the 40 handle controlling the reversible gearing, with the result that the rolls are sometimes actually reversed while the fingers are 45 caught, thereby doing still more damage.

One of the principal objects of the present invention is to provide a wringer in 50 which the possible injury to the operator is greatly reduced, without sacrificing efficient wringing of the clothes, and which is also so constructed that the operator may quickly

release the pressure and stop the rolls by 55 manipulating the same handle or lever regularly used for starting, stopping and reversing the rolls.

In accordance with the present invention, it is proposed to use a lighter pressure between the rolls than ordinarily employed, 60 provide a spring construction which will maintain substantially the same pressure as the rolls separate, and make the rolls softer and more yielding, so that serious injury is 65 not likely to result when the fingers or hand are drawn into the wringer, while at the same time the clothes are satisfactorily wrung out under ordinary working conditions. 70

In addition to minimizing the injury that the wringer will cause, my improved wringer is arranged so that one operating handle or bar, preferably extending across the top of the wringer where it can be most conveniently operated, is used for starting, stopping and reversing the rolls, and also for applying and releasing pressure to the rolls. It is believed that, since the operator uses this handle regularly for stopping the rolls, this same handle will be instinctively operated in case the fingers are caught, thereby automatically releasing the pressure and stopping the rolls. Sometimes the hair or clothing of the operator may get caught between 85 the rolls, and since these will wind up on the rolls and cause serious injury, even with the pressure released, provision is made in the present invention for automatically stopping the rolls as well as releasing the pressure. 90

Other features of the invention consist in an improved drain board arrangement; providing swinging guide boards arranged to minimize the tendency of clothes to wrap around the rolls and capable of yielding if this occurs without tearing or injuring clothes; supporting and housing the gears and bearings to keep water away and to obviate exposed moving parts to catch the clothes of the operator; and providing a 95 construction in which both the upper and lower rolls may be readily removed for inspection or cleaning, and in which the parts are accessible for replacement of rolls, bearings, or other parts. 100

Other specific objects and advantages of the invention will appear hereinafter.

In the accompanying drawings, Fig. 1 il-

illustrates a front view of the wringer, with certain parts in section;

Fig. 2 is a vertical section through the reversing gearing;

Fig. 3 is a fragmentary horizontal section taken on the line 3—3 of Fig. 1 and Fig. 2.

Fig. 4 is a vertical transverse section through the wringer;

Fig. 5 is a vertical section through the bearings and spring devices at one end of the wringer, said section being taken on the line 5—5 in Fig. 1, the operating handle being in the neutral or middle position;

Fig. 6 is a view similar to Fig. 5, with the operating handle in one of its working positions;

Fig. 7 is a view showing the position of the parts in Fig. 6 when the upper roll is lifted by something between the rolls;

Fig. 8 is a diagrammatic view illustrating the effective moments of the spring arrangement shown in Figs. 6 and 7, corresponding to different positions of the upper roll;

Fig. 9 is a vertical section showing an end view of the operating handle and indicating its different positions;

Fig. 10 is a fragmentary vertical section through one end of the wringer, illustrating a modified construction arranged to permit reversal of the rolls without releasing the pressure;

Fig. 11 is a view similar to Fig. 10 and shows a further modified construction; and

Fig. 12 is a detail section on the line 12—12 in Fig. 11.

The preferred embodiment of the invention shown in the accompanying drawings is designed so as to be applicable to domestic clothes washing machines, but since this washing machine may be of any well known or suitable type, its construction has not been illustrated. Wringers for washing machines are commonly supported by a swinging arm or bracket, in order that the wringer may be used to advantage in wringing clothes between different stationary tubs or receptacles, without moving the machine.

In the particular construction illustrated, this wringer supporting bracket B is preferably made of one casting, comprising in general a hollow head forming a casing or housing G for the reversing gearing, and a horizontally extending arm. While this bracket B may be supported on the washing machine so as to swing horizontally in any suitable manner, in the particular construction illustrated, the bracket is formed with a flange 1 which fits down over a flange or head 2 on a tubular member 3 supported at one corner of the washing machine (not shown). The bracket B carries a spring-pressed locking plunger 4, adapted to enter notches 5, formed in the head 2, so as to lock the bracket in its different positions.

In order to prevent sagging of the bracket B, a pipe 6 is attached thereto and extends down in the tubular member 3 where it bears against pads formed on the inside of said tubular member.

The wringer structure shown comprises in general, a reversing gearing and clutch mechanism in the case or housing G; two end castings C and C¹ which are fastened by screws 7 or the like to shelves formed on the wringer bracket B and which support and enclose the springs for applying pressure to the rolls; and an operating bar or handle H, extending across the top of the wringer, which is operatively connected to the clutch controlling the reversing gearing, and which also acts to apply and release the pressure between the rolls.

Either one, or both, of the upper and lower rolls R and R¹ of the wringer, are made soft and yielding, so that, under a comparatively light pressure, the surfaces of the rolls will be deformed and accommodate themselves to irregularities in the thickness of the clothes passing between the rolls, and will maintain a pressure on all parts of these clothes as they pass through, thereby pressing out the water from the thinnest parts as well as from the thicker parts or bunches. This desired softness may be obtained by modifying the composition and treatment of the rubber; and to the same end, I preferably employ rolls of larger diameter than ordinarily used, for example, 2½ inches in diameter instead of 1¾ inches. The rubber of these rolls is molded and firmly attached to shafts in the usual way and I prefer to make these shafts as small in diameter as consistent with strength and durability, so that they may spring slightly.

The rolls R and R¹ are supported in bearings in the two end castings C and C¹ and since the construction of these end castings, together with the spring arrangement for supporting and exerting the desired pressure on the rolls, is substantially the same, a description of one will suffice for both in most respects.

The shaft for the lower roll R¹ passes through a slot 8 in the end casting C or C¹, and rests in a half-round groove in a bearing block 9 which is seated in a recess in said end casting (see Figs. 1 and 5). The bearing blocks 9 are preferably made of wood, such as lignum vitæ, or some other suitable wood impregnated with tallow or paraffin. The shaft of the upper roll R is journaled in a bearing block 10, of similar material, which is carried by the outer end of a bifurcated rocking lever 11 (see Fig. 5), said lever having a round reduced portion 11^a on which the bearing block 10 is swiveled, being held in place thereon by a washer and suitable transverse pin. The bifurcated ends of the lever 11 are pivotally supported

on a pin 12 in the end casting C. Also journaled on the pin 12 is a cap or cover 13, the edges of which telescope with the edges of the corresponding end casting.

5 The pressure between the rolls is provided by a compression coiled spring 14, which is carried in a stirrup 15. This stirrup 15 extends down between the bifurcations of the lever 11, and is provided with side extensions 10 overlying said bifurcations and having knife edge contact with a notch therein, as best shown in Fig. 5. The lower end of the spring 14 rests on the cross piece of the stirrup 15, being retained in place by a boss integral therewith. In the upper end of the 15 spring 14 is a flanged follower 16, and in the cap 13 is an adjusting screw 17 engaging said follower, preferably with point contact. The spring 14 is put under the desired initial 20 tension when assembled, and its expansion is limited by an adjustable screw 18 passing through a slot in the cap 13 into a lug integral with the lever 11. It will be observed that the spring 14 in this construction serves 25 to urge apart the rocking lever 11 and the cap 13, but when the caps 13 are moved down, the tension of the spring is transferred to the upper roll. This is accomplished by shifting the operating handle H 30 from its middle position in one direction or the other.

Fastened to the outer wall of each cap 13 is a headed pin 19 carrying a revoluble roller 20. The handle H, as shown, is made up of 35 two end pieces 21 and 21^a, and a tubular cross bar 22 fastened in sockets therein. One of the end pieces 21 is clamped to a stud 23 rotating in a hole in the outer wall of the end casting C¹, substantially in line with 40 the axis of the lower roll R¹. The other end piece 21^a is pivotally supported about the same axis in a manner to be described later. Each of the end pieces 21-21^a is formed with an interrupted cross web 24 (see Fig. 45 9), constituting two cam faces and two concentric portions arranged to engage the corresponding roller 20. These side pieces 21-21^a are preferably made channel shape in cross section for strength and lightness, 50 and one of the side webs is partly cut away as shown in Fig. 9, to permit the corresponding roller to be swung out clear of said side piece. The side piece 21^a is preferably provided with a spring-pressed ball 25, adapted to be projected into recesses in the side wall of the corresponding end casting C, so as to yieldingly hold the handle H in its different positions.

The wringer rolls are connected together 60 in the usual way by cog wheels 26, and the lower roll is driven. A shaft 27, within the tubular member 3 is driven from the washing machine gearing in some suitable manner, as shown, this shaft has a lost motion 65 pin-and-slot connection with a vertical shaft

28 journaled in upper and lower bearings formed in the head of the wringer bracket B. This shaft 28 has a collar 29 pinned thereto at its upper end, said collar being preferably disposed in a recess in the head casting 70 closed by a sheet metal cover, as shown in Fig. 1. The shaft 28 extends through the gear casing or compartment G, which is provided with a detachable cover plate 30 permitting assembly of the parts and giving 75 access to the gearing for inspection or repair. On the shaft 28 are loosely mounted two bevel pinions 31 and 32, meshing with a bevel gear 33. The bevel gear 33 is formed with a hollow stud, having a squared recess 80 in the bottom thereof loosely receiving the squared end of a short coupling shaft 34. This coupling shaft 34 has a socket head to receive the flattened end of the shaft of the lower roller R¹. The hub of the bevel gear 85 33 is journaled in a sleeve 35, which in turn is supported in a bearing portion of the wringer bracket B. The end piece 21^a of the handle H has a split hub at the lower end which is clamped to one end of the sleeve 35 by bolt 36, and is also keyed thereto, as shown in Fig. 9. The other or inner end of the sleeve 35, which is within the gearing casing G, is formed with an integral mutilated gear 37 (see Fig. 2) which cooperates 90 with a toothed sector 38 to rock a stub shaft 39, as the handle H is swung back and forth. The stub shaft 39 has its ends journaled in bearing pockets in one wall of the gear case G and in the cover 30, as shown in Fig. 3; and integral with said stub shaft is a bifurcated clutch shifter 40, which fits in a circumferential groove in a clutch member 41 splined to the shaft 28. The clutch member 41 is formed with suitable teeth, and the hubs of the beveled pinions 31-32 are formed with similar teeth, so that as the clutch member 41 is moved up and down from the neutral position shown, into engagement with one or the other of the pinions 31-32, the bevel gear 33 is rotated 100 in one direction or the other, and drives the lower wringer roll in the corresponding direction.

Instead of a movable drain board, two drain boards 42-42^a are bolted to the wringer bracket B, and above these is a rocking deflector board 43 pivotally supported by screws or the like at its ends to the end castings C and C¹. These drain boards, being firmly fastened, cannot slip or tilt out of position with the weight of the clothes. Also, while the drain board on the in-going side of the wringer serves to drain the water back into the machine or tub, the one on the outgoing side deflects the clothes outward, so that they drop directly into the next tub or basket, rather than pile up directly behind the wringer.

The guide boards 45-45^a are pivotally 120 125 130 connected to the side pieces 21-21^a and the

1 supported on fixed pins 46 to swing in and out with respect to the rolls, and are kept in their inner position by their own weight. I preferably arrange these guide boards so that their inner edges are close to, and perhaps even rub on the lower roll, so as to catch clothes sticking to the rolls and thereby prevent them winding up on the rolls. Since these guide boards may swing out away from the rolls, they may be pushed away in case clothes should happen to wrap around the rolls, without injuring the guide boards or tearing the clothes.

When using the wringer, the handle H is moved from its middle position shown, in one direction or the other, according to which way it is desired to have the rolls turn. While the gearing connections may be arranged either way, I prefer to fix it so that movement of the handle toward the operator causes the rolls to rotate in a direction to wring clothes away from the operator, this particular arrangement being selected with the idea that a person getting the fingers caught will instinctively push away with the other hand. As the handle H is shifted, the sleeve 35 fastened thereto is partly turned, and this movement in turn through the cooperation of the parts 37-40 shifts the clutch member 41, and starts the rolls turning. Also, as the handle H is shifted, the webs 24 of the end pieces 21-21^a thereof engage the rollers 20, and by a camming action, force the rollers 20 downward, thus forcing down the caps 13 and putting pressure on the rolls. The wringer may now be used in the regular way. If it is desired to stop the rolls, without removing the pressure, the handle H is restored to an intermediate position between its middle and full extreme (see Fig. 9), where the clutch member 41 is disengaged and yet the pressure is maintained. This permits the operator to stop the wringer, in order to better adjust the clothes, if desired.

If the operator should happen to get the fingers caught between the rolls, a simple movement of the handle H to its middle or neutral position automatically releases all the pressure, and also instantly stops the rolls. The operator can not push the handle H too far and reverse the direction of the rolls, because the instant the handle gets in the middle position, the tension of the springs throws up the rollers 20, and with the upper roll raised up by the fingers or hand, the rollers move up too far to be engaged by the cam edges of the webs 24. In other words, whether the handle is moved quickly or slowly to the neutral position, the pressure is automatically released and the rolls stopped; and if there is anything like the fingers between the rolls, the device is locked against reversal. The handle, however, can be easily swung from one extreme

position to the other to reverse the direction of the wringer rolls when there is nothing between the rolls.

One very important feature of the invention relates to the provision made for keeping the pressure of the rolls the same, or causing it to change to any desired extent, as the rolls separate. Experiments have indicated that very little if any, more water is squeezed out by high pressures between the rolls, than with a moderate pressure, of say, 50 pounds, provided the surface of the rolls maintain reasonably close contact with all parts of the material, that is, provided the clothes are not fed through unevenly or in bunches, so that some parts are not squeezed at all. When the thickness of the clothes passing through the rolls is uneven, the thinner part may not be squeezed at all, because the rolls are held apart by the thicker part. Increasing the pressure between the rolls, of course, compresses the thicker part of the material somewhat more, and tends to bring the rolls to bear upon the thinner parts. There is evidently a limit, however, to which increasing the pressure does any good in this respect. Also, excessive pressures to obtain this result are injurious to the clothes, crushing buttons, fasteners or the like.

To take care of these conditions, it is proposed according to this invention to employ a roll for either the upper or lower roll or both, which is sufficiently soft to be compressed and deformed by a moderate pressure, in order that the surface of the roll may shape itself to the uneven thickness of the clothes passing through, thereby squeezing to some extent the thinnest parts of the clothes. With such soft and yielding rolls, it is possible to obtain the desired wringing action under all ordinary conditions with a moderate pressure, and this pressure may be substantially the same as the rolls separate, or perhaps increase slightly. With this end in view, I have devised an improved spring arrangement, for use in connection with such soft rolls, which permits the pressure between the rolls to be maintained either substantially constant, or increase, or decrease, as the rolls are separated. With this arrangement, the injury that may be caused to the fingers or hand by the wringer is much reduced, since the pressure does not materially increase as the rolls separate, and since the rolls are not so hard and unyielding, as in the present wringers.

Referring to Figs. 5 to 8 inclusive, the pressure between the rolls is obtained from the tension of springs 14 which are supported and connected to the upper roll in such a way that the pressure on the rolls will remain the same, or increase, or decrease, as desired, as the rolls separate. The spring 14 at each end of the wringer is put

under a certain tension when the parts are assembled; and this tension may be further adjusted by the hand screw 17, to take care of the varying conditions existing in practice. When the handle H is in the middle position, as shown in Fig. 5, the cap 13 is free to move upward, and there is no pressure between the rolls except that due to the weight of the upper roll, cap 13, spring 14 and associated parts. The screw 18 holds the spring 14 tensioned, since it prevents the cap 13 and rocking lever 11 being spread apart by said spring. When the handle H is shifted and the roller 20 is forced downward, as shown in Fig. 6, the head of screw 18 is moved out of contact with the cap 13, and the expanding force of the spring 14 is then transferred and directly applied to the upper roll. On account of the small downward movement of the cap 13 to accomplish this result, and the extent of movement of the handle H available, the parts may be constructed so that little effort is required to shift the handle.

With the parts of the spring arrangement in the normal position, as shown in Fig. 6, when the upper roll is raised by something passing between the rolls, the rocking lever 11 is swung slightly upward, and the spring 14 correspondingly compressed; but at the same time the effective moment or lever arm of the spring is changed, so that the pressure now existing between the rolls may be the same, or smaller, or larger, than when the rolls were in contact, depending upon the size and proportioning of the parts. The position of the rocking lever 11, and associated parts, when the upper roll is lifted is shown in Fig. 7, and by a comparison with Fig. 6, it can be seen that the line of action of the spring 14 has been changed at the same time that it has been compressed. Fig. 8 illustrates this diagrammatically. The line 50 shows the line of action of the spring 14, and the line 51 the length of the lever arm through which the expanding force of the spring acts on the rocking lever 11, in the case where the rolls are in contact; and the line 52 shows the line of action of the spring, and the line 53 the length of the lever arm, in the case where the upper roll has been raised. It will be observed that the distance 53 is shorter than the distance 51; and since the effective action of the spring 14 upon the upper roll depends not only upon the tension of the spring, but also its moment about the axis of the rocking lever 11, it will be evident that, as the upper roll is raised, the moment of the spring may be changed to compensate for the increased tension of the spring, with the result that about the same pressure between the rolls may be maintained regardless of their operation. The parts may be varied or their proportions changed so as to obtain the par-

ticular result desired. Thus, there is provided an improved spring arrangement, by means of which any variation in the pressure between the rolls as they separate may be provided, accordingly as conditions of safety and efficient wringing may require.

It sometimes happens that clothes wind up on the lower roller. When this happens, if the clothes are not wrapped around the roller to any great extent, the handle H may be pushed directly over to the other extreme position to reverse the rolls and unwrap the clothes. If the bunch of clothes between the rolls is so thick as to prevent such reverse movement of the handle H, the handle may be put in the middle position, whereupon clothes may be easily pulled out, since the rolls are disconnected from the operating gearing and the pressure is released. If desired, the construction shown in Fig. 10 may be used, which permits the rolls to be reversed with a bunch of clothes between them independently of the handle H. In this modified construction, the end piece 21^a of the handle H turns loosely on the sleeve 35, and this sleeve is actuated by an auxiliary arm 54, fastened thereto by a key and clamp arrangement similar to that already described. The upper end of this auxiliary arm 54 carries a spring-pressed plunger 55 arranged to enter a hole in the end piece 21^a, so that said auxiliary arm and handle normally move together. To reverse the rolls without shifting the handle H, the plunger 55 is pulled out, and the auxiliary arm 54 is swung over to turn the sleeve 35 and reverse the gearing. If desired, the auxiliary arm 54 may be provided with a centering spring device similar to that shown in Figs. 11 and 12 and hereinafter described, so that said auxiliary arm will automatically return to the middle position and stop the gearing as soon as released, thereby assuring that the operator will return said auxiliary arm to the proper position in the line with the handle H and latch it up with said handle.

In the modified construction shown in Figs. 11 and 12, a centering spring device is provided for the handle H, so that it must be held in its extreme positions in order to maintain pressure on the rolls and keep them in motion. With this arrangement the rolls are normally stationary, that is, when the handle is not being held over by the operator, and consequently there is no chance for them to do any damage. As soon as a garment or the like has been arranged and is ready to be wrung out, the handle H is shifted to start the rolls in the right direction and pressure is put on the rolls at the same time, in the same way as previously described. As soon as the wringing is completed, and the operator lets go of the handle, the rolls automatically stop and the pressure is re-

leased. This construction assures that the wringer will always be left with no pressure on the rolls. Also, it is certain that the rolls will be stopped when the wringer is not actually in use, thereby obviating the danger of the hair or clothes of the operator being caught as she leans over the machine or tub. Furthermore, this regular manipulation of starting and stopping the rolls will become so habitual that the handle will be instinctively and subconsciously released, in case the fingers should happen to be caught; and the stopping of the rolls and releasing of the pressure is likely to be done quicker, thus preventing damage, than if an extra movement of the free hand has to be made.

While the handle H may be spring-pressed to its middle position in various ways to accomplish the purpose just described, the particular construction illustrated comprises a tension coil spring 57 surrounding the hub through which the sleeve 35 passes, and two lugs 58-59 against which the ends of said spring engage on opposite sides thereof, one of these lugs being integral or fixed to the handle H, and the other to the gear case. When the handle H is moved in either direction, the lug 58 thereon carries with it one end of the spring 57, while the other end of said spring is held back by the stationary lug 59, thereby tensioning the spring and providing a force to return the handle to the middle position as soon as it is released.

One noteworthy feature of the invention is that the rolls may separate widely when the pressure is released, as distinctive from those constructions in which the rolls, even with the pressure released, can separate only a short distance. Referring to Fig. 5, it will be evident that there is nothing to prevent the cap 13, the upper roll, and associated parts, being raised way up, when the handle is in the middle position, so that the hand or even the arm may pass through the rolls without injury when the safety device is operated.

Another important feature of the improved construction is the provision made for ready inspection, adjustment, repair, or replacement of the several parts. When the handle H is in the middle position, the caps 13 may be swung all of the way back, carrying with them the springs 14, the rocking levers 11, and the upper roll. This permits any of these parts to be adjusted or replaced. By taking out the pins holding on the bearing blocks 10, these blocks may be removed, and at the same time the upper roll may be detached. The lower roll can also be lifted out, the outer end being lifted first to tilt the roll and disengage it first from the coupling shaft 34. With the lower roll removed, its bearing blocks may be easily replaced if required. By removing the cover plate 30 for the gear case G, all of the gears,

the clutch, and other parts in this case are exposed. In short, any part of the wringer may be very easily and quickly removed for any purpose, without aid of special tools.

The various parts of the wringer shown and described are preferably made of rustless material, such as aluminum, so far as consistent with expense, or of iron which is hot-galvanized, or otherwise suitably treated to be rust-proof. The cross bar 22 of the operating handle is preferably enameled. These details of design and construction, however, may be modified without departing from the invention. The wringer bracket B and wringer may be lifted off as a whole. The gear case G is packed with a grease or other suitable lubricant. While wooden bearing blocks are preferably used to obviate the need of lubrication and to avoid possibility of rusting, ball bearings or the like may be used if desired. In this connection, it should be noted that the bearing blocks for the upper roller are swiveled on the rocking levers 11, so that when the roll is tilted by something passing through one end, the same bearing surface will be maintained.

While all of the features hereinbefore described are preferably employed together, it should be understood that the invention is not limited to this organization. For example, the spring arrangement, or the safety device for releasing the pressure and stopping the rolls, may be used to advantage with hard rolls as now commonly used. I desire to have it understood, therefore, that while I have shown and described in detail the preferred embodiments of my invention, these particular constructions may be modified and adapted without departing from the invention.

What I claim is:

1. A wringer comprising a pair of rolls, one supported in fixed bearings and the other in movable bearings, a member acting on each of the movable bearings, a second member movable relatively to each of the first members respectively, means carried by said members for limiting their movements in a direction away from each other, a spring for each pair of said members tending to move them away from each other, and means for moving said second named members and thereby transferring the force of the springs to the movable bearings.

2. In a wringer, the combination with a pair of rolls, of means for pressing one roll towards the other comprising a rocking lever engaging each of the bearings of one of the rolls respectively, a movable member associated with each of said levers respectively, means associated with each of said levers and members to limit their movement in a direction away from each other, a spring for each of said pair of levers and members

tending to separate them, and manually operable means for moving said members toward said levers.

3. In a wringer having the lower roll mounted in fixed bearings and the upper roll in movable bearings, means at each end of the upper roll for pressing it towards the lower roll comprising a rocking lever engaging the bearing of the upper roll, an element movable relatively to said lever on an axis, means limiting the movement of said element relatively to the lever in one direction, a spring tending to move said element in said direction relatively to said lever, and means for moving both of said elements in the opposite direction relatively to their respective levers for transferring the pressure of said springs to the bearings of the upper roll, the effective line of action of the springs on said levers being shifted by relative movement of said levers and elements.

4. In a wringer, the combination with a pair of rolls, of a single operating handle for starting, stopping and reversing the rolls and for applying and releasing the pressure between the rolls, and means biasing the handle to a neutral position in which the rolls are stopped and the pressure therebetween removed.

5. In a wringer, the combination with a pair of rolls, of means including a single operating handle for starting, stopping and reversing the rolls and for applying and releasing pressure between the rolls, said means acting to release the pressure automatically as the handle is moved to its neutral position to stop the rolls, said handle being held against movement beyond its neutral position when the rolls are separated.

6. In a wringer, a handle extending along the top of the wringer and movable from a middle position toward or away from an operator standing in front of the wringer, means operated by the handle for starting, stopping and reversing the rolls, the rolls being stopped when the handle is in the middle position, and a second means also operated by the handle for applying and releasing the pressure between the rolls, the second means being formed to permit such pressure being automatically removed when the handle is in the middle position, the movement of said handle beyond said middle position being automatically prevented by the second means when the rolls are separated.

7. In a wringer, the combination of a pair of side pieces extending upwardly and pivotally mounted, one of said side pieces being at each end of the wringer, a handle connecting said side pieces at the top, a pivotally mounted device associated with elastic means at each end of the rolls and permanently connected to the rolls respectively,

and means controlled by the movement of said handle and side pieces about the axis of the side pieces for causing said devices to be turned about their pivots for applying pressure between the rolls.

8. In a wringer, the combination with the frame and rolls, of movable bearings for one of the rolls, a pivoted element respectively engaging each of the movable bearings, a spring for exerting pressure on each of said elements respectively, a single manually operated element, and means controlled by movement of said manual element for applying the force of said springs to said pivoted elements and movable bearings and for also shifting the line of action of said springs in relation to the axes of said pivoted elements.

9. In a wringer, the combination with the frame and rolls, of movable bearings for one of the rolls, a pivoted element respectively engaging each of the movable bearings, a second element pivotally related respectively to each of said first named elements, a spring related to each pair of said elements respectively tending to separate the elements of each pair, a handle, and means controlled by movement of said handle for forcing said second elements toward said first named elements for applying pressure to the movable bearings of one of the rolls.

10. In a wringer, the combination with the frame and rolls, of movable bearings for one of the rolls, a pair of elements pivoted on the frame, a second pair of elements pivotally related to said first pair of elements and adapted to exert pressure on the movable bearings, a pair of springs, said springs respectively tending to turn the second pair of elements on their pivots in relation to said first named pair of elements, a handle, and means controlled by movement of said handle for turning said first named elements on their pivots to cause the pressure of said springs to be applied to said movable bearings through said second pair of elements.

11. In a wringer, the combination with the frame and rolls, of movable bearings for one of the rolls, a pair of elements pivoted on the frame, a second pair of elements pivotally related to said first pair of elements and adapted to exert pressure on the movable bearings, a pair of springs, said springs respectively tending to turn the second pair of elements on their pivots in relation to said first named pair of elements, a handle, and means controlled by movement of said handle for turning said first named elements on their pivots to cause the pressure of said springs to be applied to said movable bearings through said second pair of elements and for shifting the line of action of said springs in relation to the pivots of said second named pair of elements.

12. In a wringer, the combination with the frame and rolls, of movable bearings for one of the rolls, a pair of elements pivoted on the frame, a second pair of elements pivotally related to said first pair of elements and adapted to exert pressure on the movable bearings, a pair of springs, said springs respectively tending to turn the second pair of elements on their pivots in relation to said first named pair of elements, a handle, and means controlled by movement of said handle for turning said first named elements on their pivots to cause the pressure of said springs to be applied to said movable bearings through said second pair of elements, and means whereby the force exerted by said springs may be individually adjusted.

13. In a wringer, the combination with the frame and rolls, of movable bearings for one of the rolls, a pair of elements pivoted on the frame, a second pair of elements pivotally related to said first pair of elements and adapted to exert pressure on the movable bearings, a pair of springs, said springs respectively tending to turn the second pair of elements on their pivots in relation to said first named pair of elements, a driving shaft, a handle and means controlled by movement of said handle for turning said first named elements on their pivots to cause the pressure of said springs to be applied to said movable bearings through said second pair of elements and for coupling said driving shaft to said rolls.

14. In a wringer, the combination with the frame and rolls, of movable bearings for one of the rolls, a pair of elements pivoted on the frame, a second pair of ele-

ments pivotally related to said first pair of elements and adapted to exert pressure on the movable bearings, a pair of springs, said springs respectively tending to turn the second pair of elements on their pivots in relation to said first named pair of elements, a driving shaft, a handle and means controlled by movement of said handle for turning said first named elements on their pivots to cause the pressure of said springs to be applied to said movable bearings through said second pair of elements and for coupling said driving shaft to said rolls and for releasing the pressure of said springs on said bearings and for uncoupling said shaft.

15. In a wringer, the combination with the frame and rolls, of movable bearings for one of the rolls, a pair of elements pivoted on the frame, a second pair of elements pivotally related to said first pair of elements and adapted to exert pressure on the movable bearings, a pair of springs, said springs respectively tending to turn the second pair of elements on their pivots in relation to said first named pair of elements, a driving shaft, a handle and means controlled by movement of said handle for turning said first named elements on their pivots to cause the pressure of said springs to be applied to said movable bearings through said second pair of elements and for coupling said driving shaft to said rolls and for releasing the pressure of said springs on said bearings and for uncoupling said shaft and for reversing the rolls.

In testimony whereof I affix my signature.

WINTHROP K. HOWE.
